PACKING BOX

Edward M. Rose and Rodney W. Epps,
Sanger, Calif.

Application May 22, 1948, Serial No. 28,648

2 Claims. (Cl. 217—13)

1

This invention relates to packing boxes and more particularly to so-called lug boxes for packing, storage, and transportation of fruits and vegetables.

It has been found that in the conventional lug boxes with nailed-on covers that the nailing of the covers on the boxes is comparatively expensive, requiring a nailing machine when speed is desired. Without a nailing machine the nailing of the covers by hand is expensive and slow. In view of this objection to the conventional method of nailing the covers or lids on lug boxes, it is one object of the present invention to provide a novel construction for the lid attachment to a lug box in which the lids are quickly, conveniently, and economically located in covering position on the boxes.

It is the usual practice to arch the lids of lug boxes whereby crushing of the contents of the box is precluded. In nailing the lid in the conventional lug box, the box is filled with fruit or vegetables and the cover is arched over and against the contents and nailed in arched condition with the inner side of the cover pressed against the contents, thereby tending to crush the fruits or vegetables. In view of this difficulty of the usual type of lug boxes it is another object of this invention to provide a novel construction for a lug box, and lid therefor, in which the ends of the box are longitudinally grooved near their upper edge with a resilient lid longer than the distance between the grooves, whereby it is installed by inserting one edge of the lid into one groove, arching the lid, and inserting the other edge in the other groove in the opposite end of the box. By this construction and method of arching the lid it is not necessary for the lid to press against the contents of the box thereby avoiding the crushing of such contents.

In attaching the lids to the conventional lug boxes, either with a nailing machine or when nailed by hand, there is considerable shaking or jarring of the contents of the box with the resultant damage thereto, especially when the contents are easily-damaged fruits, such as grapes. It is another object of the present invention to provide a lid mounting for lug boxes in which no nailing operation is necessary, the lid simply being bent or arched and located in grooves in the ends of the box.

In the conventional lug box the lid is arched over the contents of the box before nailing the lid to the box, but occasionally the cover becomes flattened or loses the arched condition

whereby the contents become crushed and the proper ventilation of the box is prevented. Therefore, it is another object of the invention to provide a box and lid construction in which the lid cannot flatten out or become unarched because the lid is arched between fixedly located grooves in the ends of the box. Therefore, the contents of fruit or vegetables does not become crushed and the box retains its ventilation opening between the arched lid and the upper edges of the sides of the box.

Another object of the invention is to provide grooves at the lower edges of the ends of the box complementary to the upper edges of the ends of the box, whereby when the boxes are stacked in superimposed relation, the grooves rest into and between the ends of the box below thereby preventing longitudinal shifting of the boxes.

Another object of the invention is to provide for a lid attachment to a lug box in such a manner that the lid cannot become loosened or get out of its confined location while the boxes are stacked.

In removing the nailed lid from the conventional lug box the contents of the box are sometimes damaged by the jarring or shaking of the box during the removal of the lid. Therefore, it is another object of the invention to provide a lug box in which the lid is removed without nail pulling simply by arching the lid further and lifting the lid from the box.

Another object of the invention is to effect greater economy in the packaging of fruits and vegetables. With the use of the construction of the present invention no nailing machine is necessary, thereby saving the purchasing, operating, and maintenance costs of such a machine. With no machine necessary for the lidding operation there is no possibility of down time due to a machine breakdown during the packing day when time saved is of vital importance. An economy is effected by the quick and easy placing of the lids onto the lug boxes, requiring no tools to achieve the simple arched placement of a lid between grooves in the ends of a box.

In the vast quantities that these lug boxes are used in the agricultural field, any economic improvement in the individual lugs looms great with the multiplicity of units packed.

Other objects and advantages of the present invention will become apparent from the following description, taken in connection with the accompanying drawings, in which,

Fig. 1 is a side elevational view of a plurality

of stacked boxes, of our invention, showing portions thereof in vertical longitudinal section.

Fig. 2 is an isometric view of a box superimposed on the upper edges of another box.

Fig. 3 is an isometric view of a box with the lid partially inserted thereon.

Referring to the details as shown in the drawing:

The lug box comprises two spaced-apart, vertically positioned, wooden ends 10. These ends are held in parallel spaced relationship by means of relatively thin horizontal longitudinal side members 11 nailed to the end members as indicated at 12. The box is provided with a bottom in the comparatively thin wooden bottom members 14 extending between the lower edges of the end members 10. The bottom and sides are formed from thin wooden boards generally referred to as shoo. The bottom member 14 is attached to the end members 10 by placing a cleat 15 against the under side of the bottom member 14 along each end thereof and nailing upwardly, as indicated at 16, through each cleat 15, through the ends of the bottom member 14 and into each of the end members 10. A lug box is thereby formed with a substantially closed bottom and sides and an open top.

This open top of the lug box is adapted to be covered after fruit and vegetables, to be packed, stored, or shipped therein, are located in the interior of the box. This covering means, or lid 18, is provided in a plurality of rectangular, relatively thin, longitudinal resilient wooden lid members 19. Other suitable resilient material may be employed in place of the wooden material. A longitudinal rectangular wooden cleat 20 is attached at 21 to each end of the plurality of lid members 19 at the upper side thereof.

This lid 18 is adapted to cover the open upper side of the lug box, and this is accomplished by providing a rectangular rabbeted recess 23 along the inner face of each of the end members 10 of the lug box, closely adjacent and parallel to the top edge thereof. Each recess 23 is formed into each box end member 10 and extended inwardly and downwardly relative to the inner face of the end member having an upper surface 24, an inner surface 25, and a lower surface 26. The distance between the upper surface 24 and the lower surface 26 of each of the recesses 23 is slightly more than the combined thickness of one of the lid members 19 and one of the end cleats 20 attached thereto. Obviously, the recesses are preferably formed in the ends prior to construction of the box.

The lid 18 is somewhat longer than the distance between the inner faces 25 of each of the recesses 23, whereby when the lid is located in covering position over the lug box, it is held in arched condition by the ends of the cover 18. The cleat 20, attached to each end of the lid members 19, and the ends of said lid members, engage the inner surface 25 of each recess 23, thereby maintaining the lid in this arched condition under compression.

Each cleat 15, secured against both ends of the bottom 14, is rabbeted longitudinally, as indicated at 23, this rabbeted or recessed portion being of rectangular shape having an upper horizontal face 29 and an inner vertical face 30. This rabbeted portion 28 is formed complementarily to the upper edge of each of the end members 10 of the box, whereby when the boxes are stacked vertically, in superimposed relation, each cleat 15, resting on each of the end members 10 of each

box, prevents each box from shifting longitudinally relative to the box on which it is resting. When the boxes are stacked, the horizontal upper face 29 of the recessed portion 28 of each cleat 15 rests on the upper horizontal edge of each of the end members 10, while the vertical inner face 30 of the recessed portion 28 of each cleat 15 engages the inner face of each end member 10 adjacent its upper edge thereby preventing this longitudinal shifting while in nested arrangement.

The lower face 31 of each cleat 15 is formed inwardly and slightly upwardly inclined complementarily to the inclined angle of each cleat 20 when the lid is in covering position over a box. This inclined face 31 of each cleat 15 on one box engages the upper inclined surface of a cleat 20 of a box therebelow when the boxes are stacked. This engagement of the inclined face 31 with a cleat 20 aids in preventing inadvertent removal of the cover when the boxes are stacked. This engagement of the face 31 with a cleat 20 also gives further frictional engagement therebetween tending to lessen transverse shifting of stacked boxes and transverse sliding of the lids thereon.

Operation

When a box is ready for use with its open upper side, the box is lined with a sheet of lining paper, and when certain fruits are packed, a shock absorbing, fibrous material is located in the bottom of the box. The fruit or vegetables, to be packed in the box, are thereafter placed into the box and filled substantially level up to the lower face 26 of each of the recesses 23 in the end members 10. The ends of the liner paper are thereafter folded in overlapped condition over the contents of the box.

The lid 18 is thereafter located to cover the box and the contents therein, by locating one end of the lid 18 with its attached cleat 20 into the recess 23 in one of the end members 10 of the box. The operator thereafter arches the lid 18 upwardly and transversely thereby shortening the distance between the two ends of the lid, whereby the opposite end of the lid and its attached cleat 20 may be inserted into the recess 23 in the opposite end member 10 by locating the opposite end adjacent the opposite recess and releasing the lid so that it may straighten somewhat causing the end of the lid and the cleat thereon to enter the recess. After the lid is thus placed in position to cover the contents within the box, the resiliency of the lid, or its tendency to straighten out, holds the lid in arched condition and also holds the cover and attached cleats 20 frictionally within the recess 23, whereby the lid is prevented from sliding transversely relative to the box.

With the boxes thus covered, the lids cannot become accidentally dislocated from the boxes and the lid is held in its arched condition by means of the fixedly spaced recesses 23, whereby the lid will not crush and injure the contents of the box. With the lid in arched condition a space is maintained between the lower side of the lid and the upper edge of each side member 11 whereby a space for ventilation is provided at each side of the box.

When the boxes are stacked, as they invariably are, the recess 28 in each cleat 15 engages the upper edge of each end member 10, thereby preventing the boxes from shifting horizontally relative to each other. Also when the boxes are stacked it will be seen that the cover is held by adjacent boxes from sliding transversely of the

box in the recesses 23, whereby the cover cannot become inadvertently removed from the box. The lid is also frictionally held from transverse shifting relative to the box by the engagement of the face 31 of each cleat 15 with the upper inclined surface of each cleat 20.

From the foregoing description, it will be seen that we have invented a lug box in which the lid is quickly, conveniently, and economically secured in covering position over the open side of the box to confine the contents within the box. It will also be seen that in eliminating the use of a lidding machine or any nailing of the lid whatsoever to the box that all vibration and jarring of the contents is precluded during the packaging thereof, thereby preventing damage and spoilage to the fruits or vegetables contained therein. It will also be seen that the lid will maintain its arched condition, thereby preventing the cover from lowering or being pushed downwardly thereby squeezing or injuring the contents of the box. It will be seen from the description that all of the objects and advantages hereinbefore stated are accomplished.

While we have herein shown and described our invention in what we have conceived to be the most practical and preferred embodiment, it is recognized that departures may be made therefrom within the scope of our invention, which is not to be limited to the details disclosed herein, but is to be accorded the full scope of the claims so as to embrace any and all equivalent devices.

Having described our invention, what we claim as new and desire to secure by Letters Patent is:

1. A structure of the class described comprising, a box having a pair of rectangular spaced parallel wooden ends, a rectangular groove rabbeted inwardly and downwardly from the inner face of each of the end members parallel to the upper edge thereof, a normally flat resilient wooden rectangular cover having a cover cleat attached along each end thereof, the cover having a length longer than the distance between the bottoms of the grooves adapted to be located between the grooves in arched condition with the ends of the cover and terminal edges of the lid cleats received by the grooves, sides interconnecting the ends of the box and overlaying the ends of the lid cleats in the grooves, and a rectangular wooden bottom cleat attached to the lower edge of each end of the box, each bottom cleat being rectangularly rabbeted along its lower outer edge complementarily to the top edge

of each end member and having an inclined adjacent lower surface complementary to the upper surface of a respective upper cleat of an attached cover where extended from its respective grooves

5 whereby superimposed boxes are prevented from shifting longitudinally of the ends of the box and whereby the cover is dependably maintained in position against lateral shifting by the sides of the box and upward movement by the groove and superimposed cleat of a box stacked thereon.

10 2. A structure of the class described comprising, a box having rectangular spaced parallel wooden ends, a rectangular groove rabbeted inwardly and downwardly from the inner face of each of the end members near the upper edge thereof, a cover consisting of a plurality of normally flat resilient wooden rectangular cover members, a cover cleat attached along both ends of the plurality of cover members, the cover 15 having a length longer than the distance between bottoms of the grooves adapted to be located between the grooves in arched condition with each cleat at the ends of the cover members having its terminal edge located in a respective groove in each end member, spaced sides interconnecting the end members and overlaying the ends of the lid cleats received by the grooves, and a rectangular wooden bottom cleat attached to the lower edge of each end of the box, each 20 bottom cleat being rectangularly rabbeted along its lower outer edge complementarily to the top of each end member and having a projection downwardly extended providing a lower surface inwardly of the rabbeted portion inclined inwardly and slightly upwardly complementarily to the upper inclined surface of the cleat at each end of the attached cover, each projection being of a length longitudinally of its respective cleat substantially equal to the spacing of the sides of 25 the box.
